CAP FOR CONTAINERS AND THE LIKE AND
METHOD OF PRODUCING THE SAMEFrederick E. Reutter, Waterbury, Conn., assignor
to Scovill Manufacturing Company, Waterbury,
Conn., a corporation of Connecticut

Application June 2, 1934, Serial No. 728,658

4 Claims. (Cl. 29—148.2)

This invention relates to caps for containers and the like and a method of producing the same.

Various users of caps, for example, packagers of toilet articles, drugs and food preparations 5 have come to demand closures that present an undefaced and unbroken outer surface, and that make a substantially uninterrupted joint with the container body.

It is an object of the present invention to provide 10 a one-piece metal cap that has an internal uninterrupted thread for engagement with the thread of a container or the like, at the same time having an undefaced outer surface.

It is a further object of the invention to provide 15 a method of producing such a cap.

With these general objects in view the invention consists in the features, combinations, details of construction and arrangements of parts which will first be described in connection with the accompanying drawing and then more particularly 20 pointed out.

In the drawing:

Fig. 1 is a view partly in elevation and partly in vertical section of a container and a cap there- 25 for constructed in accordance with the invention;

Fig. 2 is a bottom plan view of the cap;

Fig. 3 is a schematic development of the cap blank;

Fig. 4 is a similar view of the completed cap;

Fig. 5 is a sectional view (enlarged) taken on the imaginary line 5—5 of Fig. 3;

Fig. 6 is a similar view on the imaginary line 6—6 of Fig. 4; and

Fig. 7 is a sectional view taken on the line 7—7 of Fig. 2.

Referring to the drawing, the container here illustrated as an example is a wide-mouthed jar 11 having a neck 12 somewhat reduced in diameter to leave a shoulder 13. On the neck 12 is a thread 14.

The container is closed by a one-piece metal cap 15 having a top portion 16 and a skirt 17. The cap skirt is designed to take over the neck of the jar and is of a diameter substantially the same as the outer diameter of shoulder 13. The outer face of the skirt 17 presents a smooth, unbroken or undefaced surface and has an uninterrupted bottom edge, making a neat joint with the container.

In accordance with the invention in its entirety, the inner wall of the cap skirt is provided with a continuous thread-like element extending around the greater portion of its periphery and formed 55 from metal integrally rooted to the skirt wall.

As here shown as an example, the inner wall of the cap skirt has a bead-like thread 18 extending around its periphery in a helical path to accord with the pitch line of the container thread 14. The bead is formed from a narrow band of metal 5 one edge of which is integrally rooted to the skirt wall.

This may be accomplished, for example, by shaving a band of metal from the inner wall of the cap skirt, leaving the upper edge of said band integrally rooted to the wall, and forming the shaved metal into the helical thread-engaging element, e. g. rolling it into bead-like form. Since the ultimate thread-like element is on a pitch line and since there must be an entrance for the 15 container thread, it will be understood that the shaved band does not extend around a full 360°. The adjacent ends are separated by a gap of any desired and practical length, such as the gap indicated in Figs. 2, 4 and 7.

In carrying out the invention to what is now considered the best advantage, the thread-like element 18 has a substantially uniform degree of roll throughout its peripheral length. This may be accomplished, for example, by providing the 25 wall of the skirt of the blank with a helical edge, and starting the cut from such edge, the depth of the cut being substantially equal throughout the peripheral length of the band. This results in a band of uniform depth and, consequently, in 30 a uniform degree of roll.

The helical edge from which the cutting is started may be an interior edge or a bottom edge. The drawing illustrates a cap blank having an interior edge. As there shown as an example, the skirt of the cap blank (Fig. 5) has an upper portion thicker than the lower portion. To attain this end and still preserve an unbroken outer surface, the inner wall of the skirt blank is formed in any suitable manner, with two surfaces, one 35 offset from the other, thereby providing a downwardly facing shoulder 19. This shoulder, moreover, follows a helical path to accord with the pitch line of the container thread. The band of metal is then shaved from the thicker portion of 40 the inner wall of the skirt, starting the cut at the interior helical edge provided by shoulder 19 and the cut is given an equal depth throughout its peripheral length. As a result, the rolled up bead 45 is on a helical line but has a uniform degree of roll throughout.

If desired, the cut may be started from a bottom edge. In that case, the skirt of the blank may be of uniform thickness, and is formed with a helical bottom edge. Because of this helical bottom 55

edge, the skirt of the blank is made longer than the desired cap skirt. The shaving is started from the helical bottom edge of the cap blank, the cut again having a uniform depth throughout its 5 peripheral length. To complete the cap, the edge of the skirt of the blank is cut off on a right line, below the thread, to true the edge and to give the skirt the desired length.

If desired, the skirt of the cap blank may, in 10 any event, be made longer than the desired skirt and cut down to proper final length after the shaving and rolling operation. This is indicated by the broken lines in Fig. 7.

What is claimed is:

15 1. A one-piece metal screw cap for containers or the like, comprising a top portion and a skirt, the skirt having an undefaced outer surface, and the inner wall of the skirt having a continuous thread-like bead extending around the greater 20 portion of its periphery in a helical path and formed from metal integrally rooted to said inner wall, said bead having a substantially uniform degree of roll throughout its peripheral length.

2. The method of forming a metal screw cap 25 for containers and the like, which comprises forming a cap blank having a top portion and a skirt,

said skirt having a helical edge, shaving a continuous band of metal from the inner wall of the skirt around the greater portion of its periphery, starting the cut at said edge and leaving said band integrally rooted to said wall, the depth of cut being substantially equal throughout the peripheral length of the band, and forming said band into a thread-like element.

3. The method of forming a metal screw cap for containers and the like, which comprises forming a cap blank having a top portion and a skirt, 10 said skirt having a helical edge, shaving a continuous band of metal from the inner wall of the skirt around the greater portion of its periphery, starting the cut at said edge and leaving said band integrally rooted to said wall, and rolling up 15 said band into a thread-like bead.

4. A one-piece metal screw cap for containers or the like, comprising a top portion and a skirt, the skirt having an undefaced outer surface, and the inner wall of the skirt having a single thread-like bead extending around the greater part of 20 its periphery, said bead being formed from metal shaved from and integrally rooted to said inner wall.

FREDERICK R. REUTTER.
